UNITED STATES PATENT OFFICE.

GEORGE DUDLEY FORT, OF AUCKLAND, NEW ZEALAND.

FLUSHING-CISTERNS.

1,321,613.

Specification of Letters Patent.

Patented Nov. 11, 1919.

Application filed April 19, 1919. Serial No. 291,317.

To all whom it may concern:

Be it known that I, GEORGE DUDLEY FORT, subject of the King of Great Britain, residing at Cromwell Road, Mount Eden, Auckland, New Zealand, have invented new and useful Improvements in Flushing-Cisterns; and I do hereby declare the following to be a full, clear, and exact description of the same.

10 This invention has been designed in order to provide improvements in the construction of flushing cisterns of the ordinary type by means of which the cistern is made more adaptable for use in connection with ships' 15 water closets. These cisterns, as at present constructed, can not be used satisfactorily in such connection as the movements of the ship, especially in rough seas, tend to disarrange the parts and also to cause a wash 20 or agitation of water in the cistern that leads to its splashing over and also to help such disarrangement of the parts.

The present invention provides by its construction against any disarrangement of the 25 parts or any movement or agitation of the water in the cistern through the changes in position assumed by the cistern in the movements of the ship and thereby provides for the satisfactory use of this class of flushing 30 apparatus in ships.

To obtain these objects the cistern is provided with a cover that is of such a depth as to extend to the level of the water provided for by the float valve, and which cover is 35 formed with recesses in its underside to receive the ball of the float valve and the top bend of the discharge siphon, which necessarily extend to higher levels than the top-most level of the water. It is also provided 40 with an opening through it to permit of the passage of the discharge valve lifting chain, and this valve is arranged within a guide or sleeve that keeps it in position above its seat in all circumstances. The cistern is also 45 provided with a divisional plate extending across it, at its middle, this plate having a vertical slot to act as a guide for the lever of the float valve and thereby to keep such valve from lateral movement, while the plate 50 itself serves to assist in keeping the water in the cistern from being agitated.

The invention is illustrated in the accompanying drawings, in which:—

Figure 1 is a longitudinal section of the 55 cistern showing the improvements.

Fig. 2 is a cross section thereof on the line 2—2 of Fig. 1 and looking in the direction of the arrow.

A is the cistern which is provided with the usual valve B controlling the inlet from the main B' and lever and float C operating such valve, and also with the usual siphon discharge D having its operating valve D'. In this invention this valve is surrounded by a cylindrical guide E fixed to the valve seat 60 and serving to hold the valve from any lateral movement while allowing it to rise and fall to perform its usual functions. The valve is thus maintained on its seat under all circumstances and variations in the angle 65 of the cistern.

F, is the cover which is made to form a watertight joint with the top and is shaped so that it dips into the cistern with a flat surface, that is on the level of the water in 70 the cistern when it is full and as regulated by the float valve. G is the recess in the underside of the cover made to allow of the float C rising on the water to the necessary height to provide for the level reaching the 75 underside of the cover, and H is the recess to provide for the bend of the siphon being carried above the water level, as is required in the working of the siphon.

J is a small sleeve running down through 80 the cover through which the chain K for attaching the lever M to the operating valve D', is carried. This lever M is pivoted on the top of the cover in any approved manner.

N is the division plate extending across 85 the cistern at its middle and serving to divide the cistern into two chambers. This plate is formed with a slot N' extending down it and the float lever of the inlet valve B passes through the slot which therefore 90 acts as a guide to retain it from side sway. The slot also acts as a passage for the water from one compartment to the other in the discharging and filling operations of the 95 cisterns.

100 It will be seen that by dividing the cistern into two and by forming the cover so that it engages the top surface of the water, no relative change of the water in the cistern can take place in the variations in the 105 angle of such cistern. Consequently the cistern is in a condition for working properly under all varying circumstances of this nature. The other constructional improvements providing as they do for the parts 110

being kept in proper position also assist in this satisfactory working of the flush at all times.

I claim:—

5. 1. In flushing cisterns, a cover adapted to fit over the top of the cistern and shaped to enter such cistern and engage with the surface of the water therein when the cistern is filled, such cover being made with recesses 10 in its underside to receive the float of the inlet valve lever and the top bend of the discharge siphon substantially as and for the purposes herein specified.
15. 2. In flushing cisterns, a divisional plate extending across the middle of the cistern and formed with a vertical slot therein

through which the float lever of the inlet valve passes in combination with a cover fitting over the top of the cistern and shaped to enter such top and engage with the surface of the water when the cistern is full and having recesses in its underside to receive the float of the inlet valve and the top bend of the discharge siphon, substantially as and for the purposes herein specified. 20 25

In testimony whereof I have signed this specification in the presence of two subscribing witnesses.

GEORGE DUDLEY FORT.
